[57] CLAIM

The ornamental design for a bedside table, as shown and described.

DESCRIPTION

FIG. 1 is a perspective view showing the front, right and top surfaces of a bedside table embodying the design of the invention;

FIG. 2 is an elevational view of the rear of the bedside table of FIG. 1;

FIG. 3 is an elevational view of the right side of the bedside table of FIG. 1;

FIG. 4 is an elevational view of the left side of the bedside table of FIG. 1;

FIG. 5 is a top view of the bedside table of FIG. 1; and

FIG. 6 is a bottom view of the bedside table of FIG. 1.

FIG. 1FIG. 2*FIG. 3*FIG. 4*FIG. 5*FIG. 6
